FRANKFURTER PACKAGING MACHINE

John R. Litty, Goshen, N.J.

Application June 15, 1954, Serial No. 436,821

4 Claims. (Cl. 53—124)

This invention relates to a compression packaging machine for frankfurters and the like and has particular reference to a machine for compacting and inserting articles such as frankfurters in bags.

The packaging of frankfurters and similar articles in bags is a matter of some difficulty when it is desired to have the final package compact and, accordingly, more susceptible to ready handling and stacking. Generally, the packaging desired, say for a dozen frankfurters, would involve providing a rectangular array of four by three frankfurters which should be compacted into a rectangular bag. For proper compactness, the normally approximately circular frankfurters must be straightened out into parallelism and compressed to roughly approximately rectangular or square shapes to secure a minimum dimensional final rectangular package. It is the broad object of the present invention to provide a machine which may receive a generally rectangular but uncompacted assembly of frankfurters and which will compact this assembly into proper shape for delivery into a presented bag. The compacting is carried out beyond the degree which will ultimately occur in the final package, so that when the frankfurters are released in the bag they will expand to some extent and stretch the bag walls. In this fashion, a suitable final package is secured.

Hereinafter when the word "frankfurter" is employed, it is employed as referring to frankfurters, sausages and similar articles capable of being compressed or deformed.

The foregoing and other objects of the invention particularly relating to details of construction and operation will become apparent from the following description, read in conjunction with the accompanying drawings, in which:

Figure 1 is an elevation of the delivery end of the improved machine;

Figure 2 is a side elevation of the same looking at the right-hand side of Figure 1; and

Figure 3 is a plan view of the same.

The drawings illustrate a preferred form of the machine which comprises a frame 2 consisting of various individual frame parts, including the upstanding frame portions 3 and 5, which will be evident from the drawings and, therefore, requires no detailed description. The frame supports a delivery snout which comprises an upper plate 4, a lower plate 6, and a pair of side plates 14 and 16 arranged in convergent fashion in the direction of delivery. The upper plate 4 is secured to the frame portions 3 and 5 and may extend approximately horizontally as shown. The lower plate 6 slopes upwardly in the direction of delivery and is carried by a block 10 pivoted on a cross pin 8 mounted in the frame portions 3 and 5 and urged clockwise, as viewed in Figure 2, by a leaf spring 12 the upper end portion of which engages the right-hand face of the block 10 and the lower end portion of which is secured to a frame part 7. The side plates 14 and 16 converge in the direction toward the delivery end of the machine and are secured to

2

blocks mounted upon upright shafts 18 and 20 which are journaled in the frame portions 3 and 5, respectively, and at their lower ends are provided with blocks 22 and 24 against which bear the outward ends of horizontally extending leaf springs 26 and 28 the inward ends of which are secured to the frame part 7. As will be evident from the drawings, these springs 12, 26 and 28 serve to maintain yieldingly the convergent arrangement of the several plates with respect to the fixed plate 4 to provide a snout over which there may be slipped to receive the frankfurters a bag of generally rectangular shape.

In order to compact the frankfurters there are provided convergent arrays of rollers which serve to guide and advance the assembled frankfurters as a group. The upper rollers, journaled in the frame portions 3 and 5, are indicated at 30 and form an array converging downwardly toward the delivery end of the machine, the rollers being successively shorter from the receiving toward the delivery end. A similar lower array of rollers 32, journaled in the frame portions 3 and 5, is provided.

Similar vertical sets of rollers 34 and 36 are provided, these being provided with shafts which are journaled in the frame portions 3 and 5, respectively. As will be evident particularly from Figures 2 and 3, these four sets of rollers provide a converging passageway of generally rectangular cross-section through which the frankfurters may be advanced.

Each of the rollers 30 has its shaft mounted in the frame and at one end each shaft is extended through the frame, toward the right as viewed in Figure 3, and has secured thereto a gear 38. The lower rollers 32 likewise have their shafts mounted in the frame and these shafts extend through the frame and have secured to them gears 40. Upper idlers 42 mounted on fixed studs in the frame mesh with and interconnect adjacent pairs of the gears 38. Similar idler gears 44 are likewise mounted on fixed studs and interconnect the adjacent pairs of gears 40. One of the upper rollers 30 and one

of the lower rollers 32 have their respective shafts further extended to carry intermeshing gears 50 and 52 of the same diameter, and the lower of these gears meshes with a gear 54 which is secured to a shaft 55 mounted in bearings in the frame and carrying a sprocket 56 through which rotation may be imparted to shaft 55 by means of a chain drive from a motor (not shown). In use the machine is driven so that, as viewed in Figure 2, the gear 50 rotates clockwise and the gear 52 counterclockwise. The rollers of the sets connected to them

then rotate in the same direction. To package a group of frankfurters, a partially opened bag is slipped upon the snout formed by the plates 4, 6, 14 and 16 and there is then inserted into the right-hand end of the machine, as viewed in Figure 2, a roughly rectangular array of frankfurters, for example, four frankfurters wide and three high. As the frankfurters are inserted, they are gripped by the rollers at the receiving end and are advanced toward the left, as viewed in Figure 2, being straightened and considerably compressed as they are delivered between the plates of the snout. As such delivery takes place, the plates 6, 14 and 16 are forced outwardly against the action of the springs 12, 26 and 28 and when that occurs the walls of the rectangular bag are extended. The delivery of the frankfurters then continues, the compressed assemblage being forced into the bag within the bounds of the guiding plates. Finally, the plates being thin and smooth, the bag may be pulled outwardly from the plates containing the compressed frankfurters. The compression effected in the machine is beyond that which exists in the final package, the frankfurters or other articles packaged expanding tightly against the walls of the bag and providing a compact

package. Following the removal of the package the plates 6, 14 and 16 are returned to their original positions for more convenient reception of another bag.

It should be noted that while the machine is preferably operated with power-driven rollers, the machine may be operated without the rollers, in which use the articles being packaged can be pushed through the rollers by a ram which may be hand operated.

By compressing or deforming the articles and keeping them compressed as they are being inserted into a bag it is not only possible to use a smaller bag but it is also possible to make a tighter package having only a minimum amount of air space. Thus, the machine provides an improved package with a saving in the cost of labor and bag material.

It will be clear that various details of construction may be changed without departing from the invention as defined in the following claims.

What is claimed is:

1. In apparatus for packaging articles, means forming a passage substantially rectangular in transverse section and having walls converging from the inlet toward the outlet end of said passage comprising a plurality of rollers each extending across a wall of said passage, said rollers being arranged in four sets respectively lining the four walls at the inlet end of said passage, and a delivery snout including a plurality of plate members respectively lining the four walls at the outlet end of said passage and extending in longitudinal continuation respectively of said four sets of rollers, said plate members being adapted for receiving the open end of a bag fitted thereover, and means mounting said plate members

5

for yielding movement outwardly relative to one another under the influence of an article moving therebetween, thereby to open said bag for receiving said article, said rollers and said plate members being conjointly operative to compress said article to a predetermined size progressively as the same moves through said passage to said bag.

2. Apparatus as defined in claim 1 wherein the rollers of each set thereof are disposed in close adjacent relation to one another and respectively opposite the rollers of the opposed roller set, and the rollers of each pair of adjacent roller sets are disposed in staggered relation.

10 3. Apparatus as defined in claim 1 wherein the rollers of each set decrease in length successively in the direction of convergence and are disposed in close adjacent 15 spaced relation to one another and respectively opposite the rollers of the opposed roller set, and the rollers of each pair of adjacent roller sets are disposed in staggered relation.

20 4. Apparatus as defined in claim 1 wherein the delivery snout comprises a rectangular array of four plate members spring biased against movement relative to one another, and certain of said plate members are mounted for pivotal movement, against said spring bias, respectively about axes extending across the passage walls.
